UNITED STATES PATENT OFFICE.

PHILIP MUELLER, OF DECATUR, ILLINOIS, ASSIGNOR TO H. MUELLER MFG. CO., OF DECATUR, ILLINOIS, A CORPORATION OF ILLINOIS.

SANITARY DRINKING-FOUNTAIN.

1,157,173.

Specification of Letters Patent.

Patented Oct. 19, 1915.

Application filed May 11, 1912. Serial No. 696,695.

To all whom it may concern:

Be it known that I, PHILIP MUELLER, a citizen of the United States, residing at Decatur, in the county of Macon and State of Illinois, have invented new and useful Improvements in Sanitary Drinking-Fountains, of which the following is a specification.

This invention relates to drinking fountains, and has for its object to provide a nozzle for such fountains that may be installed in schools, public buildings, hospitals, and like places, where it can be attached to a service fitting having suitable means provided for catching the overflow water.

This invention is designed primarily to protect the nipple from which the drinking stream flows from contamination by the user's lips when drinking. This object is accomplished by surrounding the drinking stream at a suitable distance therefrom with a protecting wall or curtain of water, preferably concentric with the drinking stream, discharging upwardly from a suitable outlet at or below the plane of the nozzle outlet and at such a height that if a person while drinking attempts to put his lips on the nozzle the water forming the protecting wall or curtain will flow into his face and nose causing great inconvenience and disagreeable, but not harmful, results.

Heretofore stationary drinking fountains have been made from which a draft of water may be obtained without the use of a cup or other vessel, but in all these devices, so far as known, the user is required to put his lips against a part of the fountain on which others, possibly those having a communicable disease, have applied their lips, or the water for drinking flows through a body of water contained in a stationary cup or bowl larger than the water inlet pipe over the edge of which cup or bowl the water escapes. Such stationary cups or bowls are objectionable, as they are liable to contain decaying vegetable or animal matter, or other disagreeable or deleterious substances accidentally or maliciously thrown therein. There are other drinking fountains which consist of a central nozzle from which exudes a small drinking stream which nozzle the user is prevented from touching with his lips by a funnel or similarly shaped bowl surrounding the same; by upwardly or inwardly projected tubes surmounted with

a ring so that the drinker's lips will be kept from touching the nozzle by his face first coming into contact with any one or more of these obstructions. Still other drinking fountains have several tubes or openings extending outward or upward from the main inlet and directing the several streams centrally so as to form a geyser-like column of water within the ring surrounding the tubes. A defect in many of the drinking fountains now in use is that the drinker's lips may be brought into contact with some part of the structure, and if his lips cannot reach the nozzle or bowl of the drinking fountain, his face or hands are almost sure to touch some one or more of the parts intended to keep the user's lips from touching the drinking nozzle.

The main feature of the invention, as stated, is to protect the drinking stream nozzle from contact with the user's face and hands by means of a concentric wall or curtain of water projected upwardly to a less height than that reached by the drinking stream and directed vertically or with an outward or inward inclination. In any case, this protecting wall or curtain will flow into the user's face if he attempts to touch the nozzle with his lips.

With this as the principal object in view, the invention consists of the novel combination of parts hereinafter described and claimed, reference being had to the accompanying drawing in which—

Figure 1 is a vertical sectional view through one form of drinking stream nozzle illustrating my invention. Fig. 2 is a similar view of a modification.

In the drawings, A indicates the casing of a drinking fountain nozzle shown in the present instance as formed with a substantial spherical head 10 on the upper end of a reduced neck 11 designed to be connected in any suitable way to a pipe conveying drinking water and preferably provided with a cut-off or cock of any well-known type familiar to all skilled in the art and therefore not necessary to illustrate.

Centrally disposed within the casing A is a tube 12 extending upwardly therein and through an opening 13 in the top of the head 10, through which tube the drinking stream flows upward to a proper height to enter the mouth of a drinker without danger of his mouth touching any part of the nozzle

unless by special effort on his part. Surrounding the upper end of the drinking tube 12 is an enlargement 14 integral therewith as in Fig. 1 or adjustable thereon as at 14^a in Fig. 2, in either instance, the outer edge or periphery of the enlargement is spaced from the wall of the opening 14, a sufficient distance to form a thin circular slit 15 communicating with the interior of the casing, through which slit an annular stream of water flows upwardly around the drinking stream but to a less height. The object of this stream is to wet the face and flow into the nose and eyes of a drinker should he lower his head while drinking sufficiently far to touch the nozzle with his lips or other part of his face. The circular slit 15 is made preferably with a slight flare, either outwardly as shown or inwardly, if desired, to direct the protecting stream toward the drinking stream, or the slit may extend vertically and the protecting stream be parallel to the drinking stream.

The tenuity and height of the protecting stream may be constant, in which case the nozzle will be arranged as in Fig. 1, or this stream may be regulated by making the enlargement 14^a, Fig. 2, in the form of a sleeve and screwing it on the drinking stream tube 12. By turning the sleeve it will move up or down on the tube 12 and owing to the inclination of the walls of the slit 15, the width of said slit will be changed and thus the thickness of the stream and its force will be altered as is evident. A nozzle thus constructed when applied to a service pipe will fill with water when the latter is turned on, some of which will flow out through the pipe 12 in a solid drinking stream and some from the casing through the thin slit 15 in the form of an annular curtain to protect the nozzle from contact with the mouth of careless or heedless drinkers.

What I claim is,—

45 1. A drinking fountain nozzle provided with a substantially spherical hollow head with an opening in the top thereof, a tube having an uninterrupted bore for the flow of the drinking stream disposed within said

head and having an enlarged upper end 50 within the opening in the hollow spherical head of a size to form a narrow annular passage communicating with the hollow head to emit an independent protecting curtain of water surrounding the drinking 55 stream and wholly separated therefrom.

2. A drinking fountain nozzle provided with a substantially spherical hollow head, a tube for the drinking stream disposed in said head, passages for discharge of a protecting curtain of water surrounding said drinking stream tube, and means adjustably mounted on the drinking stream tube for regulating the water curtain.

3. A drinking fountain nozzle provided with a substantially spherical hollow head with an outwardly flaring opening through the top thereof, a tube having an uninterrupted bore for the flow of the drinking stream disposed within said head and formed 70 with an outwardly flaring upper end within said flaring opening and spaced therefrom to form a narrow annular passage for the discharge of an independent protecting curtain of water surrounding the drinking 75 stream and directed away therefrom so as not to coalesce therewith.

4. A drinking fountain nozzle provided with a substantially spherical hollow head with an opening in the top thereof, a tube 80 having an uninterrupted bore for the flow of the drinking stream disposed within said head and having an enlarged upper end within the opening in the hollow spherical head of a size to form a narrow annular passage communicating with the hollow head and having an outwardly and upwardly flaring peripheral wall to emit an independent protecting curtain of water surrounding the drinking stream and diverging outwardly 90 therefrom.

In testimony whereof I have hereunto set my hand in presence of two subscribing witnesses.

PHILIP MUELLER.
